UNITED STATES PATENT OFFICE.

JAMES W. MCKEE, OF BROOKLYN, NEW YORK.

LATCH AND LOCK COMBINED.

SPECIFICATION forming part of Letters Patent No. 477,142, dated June 14, 1892.

Application filed March 10, 1892. Serial No. 424,434. (No model.)

To all whom it may concern:

Be it known that I, JAMES W. MCKEE, a citizen of the United States, residing at Brooklyn, in the county of Kings and State of New York, 5 have invented new and useful Improvements in Locks, of which the following is a specification.

This invention relates to locks, and more particularly to such as are operated by the 10 direct endwise movement of the key in distinction from those in which the key is required to be turned after it has been inserted in the keyhole.

The invention consists in certain novel devices and combinations hereinafter described and claimed, reference being had to the accompanying drawings, in which—

Figure 1 is a longitudinal section on the bent line x x , Fig. 2. Fig. 2 is a cross-section 20 on the line y y , Fig. 1. Fig. 3 is a horizontal section on the bent line z z , Fig. 1. Fig. 4 is a longitudinal section on the line x' x' , Fig. 5. Fig. 5 is a cross-section on the line y' y' , Fig. 4. Fig. 6 is a horizontal section on the 25 line z' z' of Fig. 4, the lock being open. Fig. 7 is a separate view of the key, taken as it appears when in the keyhole, as shown in Fig. 5.

The head A of the lock in the present example of my invention projects upward from 30 the lock-case B, to which it is fastened by screws C C, that go through the lateral extension A' of the head and are screwed into the bottom of the lock-case, the construction being such that the extension A' comes over 35 a depression in the bottom of the case in which the tail end D of the bolt E slides. The bolt is moved outward by a spring F, whose rear end bears against a stationary post G, that rises from the lock-case through a slot made 40 in the bolt, in which slot the spring F is placed, the front end of said spring pressing against the forward end of the bolt, so as to push the front end of the bolt outward to the position shown in Figs. 1 and 3.

45 The head A is inclosed in the hollow post A², which is rigidly connected with or made part of the usual cover A³ of the lock-case, the arrangement shown being such as will be suitable for a mortise-lock; but of course I do 50 not confine myself to mortise-locks. The bolt can be moved inward, so as to open the lock by pushing against the slide H, which extends

through the lock-case, so as to engage the tail end D of the bolt, as is shown in Figs. 1 and 4, the slide H moving in and out with the bolt, 55 to which it is fastened. The bolt can be locked in its outer or inner positions by means of the locking-slide I, which carries a stop J, that is moved into the notch K, Fig. 3, made for it in the side of the tail end of the bolt when 60 the bolt is to be locked in its inner position, as shown in Figs. 4 and 6, the said stop being moved behind the tail end of the bolt, as in Fig. 1, when it is desired to lock the bolt in its outer position. The locking-slide I is 65 moved to its different positions by means of the button K', which is fixed on a pin that works in a slot K², made in the lock-case.

The head A is provided with a slot A⁴ in its upper end to receive the key of the lock, said 70 slot terminating in a rectangular opening A⁵, which receives the upper ends of the tumblers L—four in number in this example, although the number may be varied—and the upper end of a lever M, that turns on a pin N, that 75 is supported in standards that rise from the extension A' of the head. The tumblers are held in a raised position on the pivot N by springs P, which are fastened by one end to the respective tumblers, and are then bent 80 back over the pivot N and their free ends braced against stationary block O, whereby the tumblers are held up by the springs with a yielding force toward the position in which the tumblers are shown in Fig. 1, where a 85 cross-bar P² from the back of the lever M extends across the backs of the tumblers into a notch P', cut on each tumbler, so that the bar acts as a stop to the tumblers and causes them to be in unison with each other and with the 90 lever M on their front faces, where they present themselves in the slot or opening A⁵ of the head. The lever M has a toe Q, that projects downward from its underside through a slot R in the extension A' of the head and 95 into a slot 1 in the tail end of the bolt.

When the key is inserted into the top of the head, it passes downward and its bottom edge strikes the ends of the tumblers and pushes them downward, so that they move 100 across the keyhole-slot A⁵ until their notches P' are freed from the cross-bar P², which action liberates the tumblers and lever M from each other and allows the tumblers to be

pushed by the key down to their lowest position, (see Fig. 4,) and allowing the notch S of the key to come in its descent down upon the projection S' of lever M and turn said lever 5 M across the keyhole-slot to the position shown in Fig. 4, where its toe Q engages the slot 1 in the tail end of the bolt and draws back the bolt to the position shown in Fig. 4, in which position the bolt is drawn back and 10 can be held in that state by operating the slide I as above explained. On moving the slide I so as to free the bolt, the bolt-spring F moves the bolt outward to the position seen in Figs. 1 and 3, and the lever M and the tumblers I move or swing back to the positions 15 shown in Fig. 1.

It will be understood that by inserting the key, Fig. 7, into the head A it comes in contact with the ends of the tumblers L and 20 pushes them downward from their positions as represented in Fig. 1 to their positions as shown in Fig. 5, their ends being pushed downward by the key and at the same time swung forward through its opening or side 25 notches toward the positions shown in Fig. 4, the tumblers being turned upon the pivot N, so as to allow their forward ends to project through the said openings of the key and to permit the notch S of the key to press upon 30 the forward projection S' of lever M, by which means the lever M is made to turn upon its pivot N and to be brought to the position shown in Fig. 4, its toe Q being made to engage the tail end of the bolt and to push the bolt back, and 35 thereby open the lock, in which operation the front ends of the tumblers and lever M are brought to the positions shown in Fig. 4, where they are seen projecting through the opening A⁵ of the head and through the openings in 40 the key.

It will be observed in Fig. 1 that before the tumblers begin their movements they are partly in line with the slot A⁴ of the head and underneath the same, and that the head U of lever M is wholly on one side of said slot A⁴. 45 As the key moves into operation the tumblers are swung forward to the position shown in Fig. 4, and the head U of the lever M moves into the perforation V of the key, Figs. 4 and 50 5. When the key is moved down to its unlocking position, Fig. 5, it will be noticed that the tumblers L, or rather the forked ends of said tumblers, and the end of lever M, with its head U, enter or fill up the hole V and all the 55 notches of the key, so that the entire keyway or opening A⁵ will be filled up or cut off, as shown in Fig. 5.

From inspecting the key, Fig. 7, it will be noticed that the lateral or side notches do not 60 correspond. In making a variety of keys said notches can be made either corresponding or not, or either side of the key may be left plain and the other notched, or the notches may be formed along the bottom edge of the key, and 65 in this way any variety of keys may be formed. The variety can further be increased by changing the form of the opening or depression V.

It will be noticed that the lever M swings transversely to the plane of motion of the bolt, and the simple insertion of the key is sufficient to secure the transverse motion of the lever to effect a withdrawal of the bolt, while if the lever swung, for example, in a plane parallel to the plane of travel of the bolt the key would first have to be inserted and then 75 rotated to properly move said lever.

To prevent the lever M being pressed down or actuated independently of the tumblers, I provide a stop or locking-tongue W, swinging on pivot or support X, and held toward 80 the lever M and tumbler L by a suitable spring Y. This locking-tongue W is so arranged as to sit squarely under the lever M and prevent motion of the same when the parts are in the position shown in Fig. 1; but the tumblers L are arranged to act laterally on the tongue W, either by the tumblers having their edges in contact with the upper end of the tongue W cut inclined or by that portion of the tongue W which comes in contact with 85 one or more tumblers being inclined. When, therefore, the tumblers are moved in advance of lever M, said tumblers move the tongue W out of the path of the lever, Fig. 4, and allow the latter to move. On the parts being 90 released the spring Y moves the locking-tongue back to its locking position. By having the free end of the tongue W broadened or formed into a head, as seen in Fig. 2, the different portions of the head can be arranged 95 so that one portion will come squarely into contact with lever M to lock the latter, while another portion is in inclined contact with one or more tumblers L to allow the latter to move or press the tongue aside to its releasing position. 105

What I claim as new, and desire to secure by Letters Patent, is—

1. The combination, with a lock-case having a keyhole-slot and a sliding bolt arranged in the case, of a pivot-pin, a series of oscillatory tumblers mounted on the pivot-pin and moved across the keyhole-slot by the insertion of the key thereinto, and an oscillatory lever mounted on the pivot-pin of the tumblers, having an arm engaging the tail end of a sliding bolt and moved by the key parallel with the tumblers across the keyhole-slot to cause the arm of the lever to retract the bolt, substantially as described. 110 115 120

2. The combination, with a lock-case having a keyhole-slot and a sliding bolt arranged in the case, of a pivot-pin, a series of oscillatory tumblers mounted on the pivot-pin, provided with notches in their back edges and 125 moved across the keyhole-slot by the insertion of the key, and an oscillatory lever mounted on the pivot-pin of the tumblers, provided with a cross-bar normally engaging the notches in the back edges of the tumblers 130 and having an arm engaging the tail end of the sliding bolt, said lever being moved by the insertion of the key in a plane parallel with the tumblers across the keyhole-slot to 135

cause the arm of the lever to retract the bolt, substantially as described.

3. The combination, with a bolt, of a series of tumblers, and a lever having an arm or connection for engaging the bolt, said lever having a head, as U, and said key having an eye or recess, as V, for receiving said head U, substantially as described.

4. The combination, with a bolt, of a series of tumblers, and a lever mounted on a common pivot or support, said lever being connected with the bolt, and an extension or base A', made to carry said pivot and provided with a head A, having a keyhole or slot A⁴, substantially as described.

5. The combination, with a bolt, of a series of tumblers, and a lever mounted on a common pivot or support, said lever being connected to the bolt, and an extension or base A', made to carry said pivot and provided with a head A, having a keyhole or slot A⁴, and a transverse opening A⁵ for accommodating the movement of the lever and tumbler, substantially as described.

25 6. The combination, with a lock-case having a keyhole-slot, a sliding bolt arranged in the case, and a spring for projecting the bolt, of a slide for retracting the bolt by hand, a locking-slide for engaging and holding the bolt when retracted, a pivot-pin, a series of oscillatory tumblers mounted on the pivot-pin and moved across the keyhole-slot by the insertion of the key, and an oscillatory lever mounted on the pivot-pin of the tumblers, having an arm engaging the tail end of the sliding bolt and moved by the key parallel with the tumblers across the keyhole-slot to cause the arm of the lever to retract the bolt, substantially as described.

40 7. The combination, with a lock-case having a keyhole-slot and a sliding bolt arranged in the case, of a pivot-pin, a series of oscillatory tumblers mounted on the pivot-pin and moved across the keyhole-slot by the in-

sertion of the key, an oscillatory lever mounted on the pivot-pin of the tumblers, having an arm engaging the tail end of the sliding bolt and moved by the key parallel with the tumblers across the keyhole-slot to cause the arm of the lever to retract the bolt, and a spring-pressed locking-tongue pivoted at one end and having its opposite end normally engaging the oscillatory lever and moved out of engagement therewith by the action of the tumblers when the proper key is inserted to move the tumblers across the keyhole-slot, substantially as described.

8. The combination, with a bolt, of a series of oscillatory tumblers, and a lever oscillating in a plane parallel with the tumblers and having an arm or connection for engaging the bolt, and a key for actuating the tumblers and bolt, said key having recesses or cut-out portions for receiving the lever and the tumblers, substantially as described.

9. The combination, with a bolt, of a series of oscillatory tumblers, and a lever oscillating in a plane parallel with the tumblers and connected to the bolt, and a locking tongue or stop placed into square or locking contact with the lever and into inclined contact with one or more tumblers, said locking tongue or stop being freed from engagement with the lever by the action of the tumblers when the proper key is inserted, substantially as de- 75

10. The combination, with a bolt, of a lever connected to the bolt, a locking-tongue for the lever, and a tumbler (one or more) for moving the locking-tongue to its releasing 80 position, substantially as described.

In testimony whereof I have hereunto set my hand in the presence of two subscribing witnesses.
